(57) **CLAIM**

The ornamental design for a garden ornament, as shown and described.

DESCRIPTION

FIG. 1 is a front elevational view of a garden ornament showing my new design;

FIG. 2 is a rear elevational view thereof;

FIG. 3 is a right side elevational view thereof, with the left side being a mirror image thereof;

FIG. 4 is a top plan view thereof;

FIG. 5 is a bottom view thereof; and,

FIG. 6 is an enlarged partial cross-sectional view thereof, drawn along line 6—6 in FIG. 3.
